(74) Attorney, Agent, or Firm—Wallenstein Wagner & Rockey, Ltd.

(57) **CLAIM**

We claim the ornamental Design for a sidewall for disposable cup, as shown and described.

DESCRIPTION

FIG. 1 is a perspective view of a sidewall for disposable cup; FIG. 2 is a front elevation view of the cup of FIG. 1; FIG. 3 is a rear elevation view of the cup of FIG. 1; FIG. 4 is a bottom plan view of the cup of FIG. 1; and, FIG. 5 is a front elevational view thereof where the cup portion is broken away for ease of illustration. Broken lines in the Figures form no part of the claimed design.
